UNITED STATES PATENT OFFICE.

HORACE F. WHITMAN, OF PHILADELPHIA, PENNSYLVANIA.

DESIGN FOR A BOX.

SPECIFICATION forming part of Design No. 19,143, dated June 4, 1889.

Application filed April 13, 1889. Serial No. 307,189. Term of patent 3½ years.

To all whom it may concern:

Be it known that I, HORACE F. WHITMAN, a citizen of the United States, residing in the city and county of Philadelphia, in the State 5 of Pennsylvania, have invented a new and original Design for Boxes, of which the following is a specification.

My design is illustrated in the annexed drawing, which represents in perspective a 10 box embodying said design.

The body A of the box is semicircular in form, having a semicircular bottom a, one flat side b, and a curved side c, and within the box is a curved partition d, parallel to the 15 side c, its ends abutting the side b. Within the space between the partition d and side c is a series of oval partitions or divisions e, forming a series of pockets x, containing bottles or other articles, and within the space

bounded by the partition d and part of the 20 side b are other partitions f, similar to the partitions e.

The leading feature of the design is a semicircular box divided by means of division-pieces or partitions into series of oval pockets x.

I claim—

The design for a box, consisting of a flat body with a straight side b, curved side c, semicircular partition d, and with oval pockets x, substantially as shown.

In testimony whereof I have signed my name to this specification in the presence of two subscribing witnesses.

HORACE F. WHITMAN.
